CLAIM

The ornamental design for a pressure washer, as shown and described.

DESCRIPTION

FIG. 1 is a perspective view of a pressure washer showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of the pressure washer taken from the circle portion in FIG. 1; and,

FIG. 9 is an enlarged view of the pressure washer taken from the circle portion in FIG. 7. The portion of the pressure washer shown in broken lines form no part of the claimed design.
